DESIGN FOR A SAFETY RAZOR

Henry Ruskin, Chicago, Ill., assignor of one-half to George E. Hale, Chicago, Ill.

Application January 31, 1947, Serial No. 136,580

Term of patent 14 years

(Cl. D22—3)

To all whom it may concern:

Be it known that I, Henry Ruskin, a citizen of the United States and a resident of Chicago, in the county of Cook and State of Illinois, have invented a new, original, and ornamental Design for a Safety Razor, of which the following is a specification, reference being had to the accompanying drawing, forming a part thereof, and in which:

Fig. 1 is a top plan view of a safety razor showing my new design;

Fig. 2 is a perspective view of the same.

I claim:

The ornamental design for a safety razor, as shown.

HENRY RUSKIN.
